Patented Oct. 27, 1925.

UNITED STATES PATENT OFFICE.

JOHN C. BOHMKER, OF BRADLEY, ILLINOIS, ASSIGNOR TO SEARS, ROEBUCK AND CO.,
OF CHICAGO, ILLINOIS, A CORPORATION OF NEW YORK.

PLOW.

Application filed October 19, 1923. Serial No. 669,472.

To all whom it may concern:

Be it known that I, JOHN C. BOHMKER, a citizen of the United States, residing at Bradley, in the county of Kankakee and State of Illinois, have invented a certain new and useful Plow, of which the following is a specification.

The invention pertains to plows, and has for its general aim the provision of a plow bottom which is especially adapted for use in tractor drawn plows wherein it is very desirable, if not essential, that the weight of the plow be reduced to a minimum.

With this aim in view, one object of the invention is to provide a construction for plow bottoms in which the frog customarily employed is eliminated.

A further improvement has to do with the construction of the plow point in a manner such that its weight is reduced without sacrificing strength and rigidity.

Still another object is to make the plow bottom of such construction that the plow share and point may be detached at will for purposes of repair or removal.

A general object is to reduce the cost of manufacture while at the same time increasing the efficiency of the plow.

In the accompanying drawings, Figure 1 is a perspective view of a plow bottom constructed in accordance with my invention.

Fig. 2 is an underside perspective view of the same.

Fig. 3 is a plan view of the plow point detached.

Fig. 4 is a view looking into the plow point from the rear end thereof while the point is detached.

The plow bottom selected for purposes of illustration, comprises generally a point 7, a share blade 8, a mold-board 9, and a landside 10. These parts are rigidly secured together in the proper relation and supported from the plow frame by means of a beam 11 having a downwardly curved lower end portion which, in accordance with the present invention, is employed in place of the usual frog as the means to which the parts may be secured for support.

The point 7 is preferably made in the form of a casting. Plow points as now commonly manufactured are made from separate pieces of steel welded together and treated to provide desirable wear-resisting qualities. This method of construction by

welding involves a relatively large number of separate operations, and the weight of the point when completed is relatively great. To lower the cost and reduce the weight, I cast the point, and in so doing I form within it a socket adapted snugly to receive the lower end of the beam 11 which latter is especially shaped for this purpose. As shown clearly in Fig. 4, my improved point comprises a landside portion 12 commonly termed among the trade a "gunnel" and a share portion 13 of a generally triangular shape (Fig. 3) integrally joined at one edge with the gunnel 12. At their forward ends, the gunnel 12 and share portion 13 terminate in a flat point 14 (Fig. 2).

At the lower edge of the gunnel 12 I provide an inwardly extending flange 15 between which and the under surface of the share portion 13 of the point is formed the socket adapted to receive the lower end of the beam 11 which latter tapers to a point as shown in broken lines at 16 in Fig. 1, in order to engage snugly in the point with a wedging action when the point is drawn rearwardly in a manner to be presently described.

For the purpose of securing the share blade 8 to the point 1, I provide in the construction of the latter a rearwardly extending lug 17 whose upper surface is substantially flush with the lower surface of the share portion 13 of the point. Said lug is apertured as at 18 to receive a bolt 19 passing through the forward end of the share blade and rigidly securing the latter and the point together with their adjoining ends in abutting edge relation.

The mold-board 9 is secured to the share 8 and to the beam 11 by suitable means. Thus I employ a plate 20 having a flange 21 at one end rigidly secured as by means of a bolt 22 to the beam 11 and by bolts 23 and 24 to the mold-board. The latter bolt also serves to fasten upon the under side of the mold-board and upon the under side of the plate 20, an angular bracket 25 having a portion 26 adapted to engage with the rear edge of the plate 20. Said bracket is apertured to receive the threaded shank of a rod 27 anchored at 28 to the underside of the share blade 8 near the rear edge thereof. Said plate 20 is so secured to the mold-board that its forward portion underlies the rear edge of the share blade as well as the rear

corner of the share portion of the point 14, and the threaded end of the rod 27 passing through the bracket 25 is provided with a nut 29 whereby the parts may be drawn 5 together.

To assist in holding the share and mold-board in proper relation, I provide a pair of blocks 30 and 31 secured respectively to the share blade and mold-board, upon the 10 undersides thereof, as by means of bolts 32 and 33. These blocks have respectively, portions projecting beyond the edges of the parts to which they are secured, as shown clearly in Fig. 2, and thus coact to hold 15 the parts in alinement.

The mold-board 9 is further secured to the beam 11 by means of a substantially U-shaped bracket 34 and bolts 35 and 36 entered respectively through the beam and the 20 mold-board.

The landside 10 is in the form of a flat blade which is secured to the outer side of the beam 11 near its lower end as by means of the bolt 22 and a bolt 37 (Fig. 1). This 25 blade is made of a thickness approximately equal to that of the gunnel 12 of the point and extends rearwardly in continuation of the gunnel beyond the rear edge of the beam 11.

30 It will be observed that the point 14, the mold-board 9 and the landside 10 are all secured directly to the beam 11, and that the latter serves through a simple downward and forward extension, the function of the 35 frog heretofore employed in securing the parts together. As a result, a substantial reduction in the weight of the plow bottom is effected.

It will be evident that by reason of the 40 fact that the point is cast it may be shaped as desired to form the socket to receive the tapered end or toe of the beam. As a further advantage resulting from casting the point, it is possible to reduce its weight.

45 Also the means for detachably connecting the share blade to the mold-board is simplified. Thus the lug 17 renders it possible to secure the point and share blade together with only one connecting rod as distinguished 50 from the two rods previously employed in plows of the detachable share type.

I claim as my invention:

55 1. A plow bottom comprising, in combination with a beam having a downwardly and forwardly extending toe portion, a point constructed to provide a socket adapted to receive said toe portion of the beam, a mold-board secured to the beam rearwardly of the point, a share blade rigidly but detachably secured to the point at the rear end thereof, and means for detachably securing the share blade to the mold-board so as to hold such parts in alinement, said means consisting of a rod having one end fastened to the share 60 blade and a device for fastening the opposite 65

end of the rod to the mold-board adapted to place the rod under tension.

2. The combination with a plow beam having a forwardly extending toe portion at its lower end, a point having a socket 70 adapted to receive said toe portion of the beam, a mold-board rigid with the beam, a share blade, means connecting the share blade to the mold-board adapted to exert a rearward pull upon the share blade, and 75 means for detachably connecting the share blade to the point whereby when the share blade is drawn rearwardly, the point is also drawn rearwardly upon the beam.

3. A plow bottom comprising a point cast 80 to provide a gunnel for the landside portion and the share portion, said gunnel having an inturned flange at its lower edge adapted to form with the share portion a socket having walls converging toward the forward 85 end of the point, said socket being adapted to receive a supporting member rigidly secured to the plow frame, a share blade having its forward edge detachably secured to the share portion of the point in abutting 90 edge relation thereto, and means for exerting a rearward pull on the share blade and thereby drawing the point onto said support.

4. The combination with a support adapted to be secured directly to a plow frame and having a forwardly extending toe portion at its lower end, a mold-board rigid with one side of said support, a landside secured directly to the opposite side of said support, a share blade having a connection with the mold board in abutting edge relation thereto, and a point adapted to fit directly over the toe of said support and connected rigidly with the forward edge of the 105 share blade, said connection between the share blade and the mold-board being adapted to draw the share blade rearwardly relative to the mold-board and thereby through the connection between the share blade and plow point to draw the latter onto said toe.

5. The combination with a plow beam having a downwardly and forwardly extending toe portion, a landside secured directly to one side of said beam rearwardly 110 of the toe portion, a mold-board, means for securing the mold-board directly to the opposite side of said beam including a plate secured to the underside of the mold-board near its forward edge and having a flange secured directly to the beam, said plate having a portion extending beyond the forward edge of the mold-board, a share blade, a rod secured at one end to the share blade near the rear edge thereof and at its other end 115 to the mold-board near the forward edge thereof, said rod being adapted to underlie said plate and having means for exerting a rearward pull upon the share blade, and a plow point adapted to fit directly upon the 120 125 130

toe of the beam and rigidly secured to the share blade at the forward end of the latter.

6. A plow bottom comprising, in combination with a beam adapted to be secured directly to the plow frame and having a downwardly and forwardly extending portion near its forward end tapering to a point, a landside secured directly to the beam near its lower end but rearwardly of said point, a mold-board, means for securing the mold-board to the opposite side of said beam including a plate secured upon the underside of the mold-board near its forward edge, said plate being also secured directly to said beam and having its forward edge portion extending beyond the forward edge of the mold-board, a plow point having a landside or gunnel portion and a share portion providing a socket between them

adapted to receive the point of the beam, 20 while the rear end of the share portion overlies one end of said plate, said plow point having a lug on its underside extending rearwardly therefrom, a share blade having its forward end abutting the rear edge of the share portion of the point and rigidly secured to said lug, a bracket rigid with the mold-board, a rod secured at one end to the share blade and entered at its other end through said bracket, said rod being arranged to underlie said plate, and a nut on the rod adjacent the bracket adapted to draw the share blade rearwardly relative to the mold-board and thereby draw the plow point onto the beam. 25 30 35

In testimony whereof, I have hereunto affixed my signature.

JOHN C. BOHMKER.
